UNITED STATES PATENT OFFICE

JOHN B. BERNHARD, OF STONELEIGH, MARYLAND

BOILER

Application filed April 18, 1929. Serial No. 356,198.

My invention relates to boilers.

The principal object of my invention is to devise a boiler which is constructed to insure a complete mixing of the combustible gases with the entering air and a consequent efficient combustion through subjecting the flow of the gases to frequent changes of direction, and further to secure an intimate contact of the hot gases with the heating surfaces of the boiler, with a view of improving the heat absorptive capacity of the unit.

A further object is to devise a boiler as above described which comprises an increase in the amount of heating surface relative to units of similar type and in which a large proportion of this surface is disposed substantially normal to the flow direction of the hot gases, breaking up the gas currents and extracting therefrom the maximum available heat.

A further object is to devise a boiler of the above type which is characterized by a quick heating response, a free water circulation, ample water capacity, and an absence of any tendency to prime or drive the water out of the unit, if the latter is used to form steam.

A further object is to devise a boiler of the character described, and particularly one of the so-called sectional type, in which the composing sections may be manufactured at a minimum cost, and labor, and which are susceptible of easy assembly, to meet a wide range of operating conditions, whether steam, vapor, or hot water.

My improved boiler is composed of a predetermined number of sections between which the hot gases pass on their way to the stack. In each section, the heating surfaces are larger in area than indicated by the overall dimensions thereof and are mutually disposed to frequently deflect the flow direction of the hot gases while passing therebetween. From this construction results two advantages; first, a thorough mixing of the combustible gases with the entering air and a consequent promotion of the most efficient combustion, and second, a positive relation of the heating surfaces to the hot gases which operates to break up the latter and to extract

therefrom the maximum amount of heat. The water content of each section is sufficiently small in relation to the amount of heating surface to insure quick steaming and a continuous rapid transfer of heat to the water, but without any danger of driving the water out of the sections, owing to the efficient mode of circulation, as hereinafter described. The hot gases are retained in contact with the heating surfaces of the sections a period of time sufficient to insure their complete combustion and an extraction of the utmost heat value therefrom. Other advantages of my improved boiler will appear in the subsequent explanation thereof as set forth in the following specification, reference being had to the accompanying drawings, and the novel means by which said objects are effectuated will be definitely pointed out in the claims.

In the drawings:

Fig. 1 is a sectional side elevation of my improved boiler, as viewed along the line 1—1 in Fig. 2.

Fig. 2 is a section along the line 2—2 in Fig. 1, looking in the direction of the arrows, the smoke box being omitted.

Fig. 3 is a front elevation of the boiler on reduced scale, showing the relation of the front, end and intermediate sections.

Fig. 4 is an enlarged section along the line 4—4 in Fig. 1, looking in the direction of the arrows, showing the relation between an adjoining pair of sections in respect of their heating surfaces and flue passage therebetween.

Fig. 5 is an enlarged section along the line 5—5 in Fig. 1, showing the relation between a pair of adjoining sections in respect of the delivery passage to the smoke box.

Fig. 6 is a sectional side elevation of the lower portions of the front, back and side sections, showing the means for effecting a circulation of water therebetween.

The numeral 10 represents my improved boiler, which for purpose of illustration will be denoted as a steam type, and which includes the usual ash pit door 11, clinker door 12, fire door 13 and flue door 14. The door 11 communicates with an ash pit 15 which

is defined by a front wall 16, a rear wall 17 and side walls 18 of any approved construction. A draft opening 19 may also communicate with the ash pit 15 in the usual manner and the passage of air therethrough may be controlled by a door 20, operable if desired by any approved type of automatic draft mechanism. A plurality of grates 21 may be also supported by the walls 16 and 17 a predetermined distance above the floor of the pit 15.

The parts just enumerated in and of themselves form no part of the improved features of the boiler, but have been set forth in detail as illustrating one type of operative environment. It is contemplated that numerous changes may be made in these elements as conditions determine, one such change being the substitution of gas or oil burners for the grates 21 as a source of combustion.

A hollow front section, or water leg, 22 is mounted above the grates 21 and comprises openings 23 and 24 which are closed by the doors 13 and 14, respectively. At the opposite end of the boiler is a plurality of back water sections, or water legs, 25, also supported above said grates and extending thereabove for a predetermined distance.

The sections 25 communicate with each other adjacent their respective bottoms by means of nipples 26 and at the tops thereof by means of nipples 27. As shown in Fig. 2, the back of the boiler is formed by an association of individual sections, but it is contemplated in actual manufacture to combine the same into a single unit covering the entire back of the boiler in the same manner that the section 22 covers the front end thereof, as shown in Fig. 3.

Bridged between the sections 22 and 25 are a plurality of end, or side, and intermediate sections with which the flue gases come into contact during their passage through the unit and which accordingly include the principal heating surfaces of the boiler. For the type of construction shown in Fig. 1, the sections 22 and 25 are spaced sufficiently apart to permit the placing therebetween of pairs of said end and intermediate sections, the sections in each group of pairs being disposed end to end. For purpose of illustration, the end and intermediate sections adjacent the section 22 will be termed front sections of the corresponding type and those adjacent the sections 25 will be termed rear sections.

Accordingly, the numeral 28 denotes the front side sections, the numeral 29 the rear side sections, the numeral 30 the front intermediate sections, and the numeral 31 the rear intermediate sections. As shown in Figs. 1 and 2, the sections 28 and 29 have approximately the same height as the front section 22, whereas the intermediate sec-

tions 30 and 31 do not extend below the upper edge of the opening 23, this arrangement forming the usual combustion space below the intermediate sections.

The construction of the intermediate sections and of the upper portions of the side sections are substantially identical, so that for purpose of description, an outline of one of the former will be sufficient. Each of the intermediate sections comprises a pair of vertical, end columns 32-32 which are connected at the bottom of the section by a duct 33, the thickness of said columns and duct being approximately the same for a purpose hereinafter explained. At the upper end of said columns, the section is enlarged to form a chamber 34 which serves as a combined steam and water space and with which said columns communicate.

A plurality of hollow fins project from one side of the body of said section, spaced from each other and parallel with the lower edge of the section. Two of said fins, denoted by the numeral 35 extend across the length of the section and project therefrom the same distance, while the remaining and uppermost fin 36 terminates short of the front column 32 and projects from the section a greater distance than the fins 35, all of these features being provided for a purpose hereinafter explained. The shortening of the fin 36 forms an opening 37 at the forward end of the section when the latter is assembled with other sections in the boiler.

A plurality of openings 38 are formed through the body of the section within the margin defined by the columns 32, duct 33 and chamber 34, and above and below the fins 35 and 36. In addition, the portion of the section within said margin is depressed so that the thickness thereof is less than that of said columns and duct for a purpose hereinafter explained, the provision of the openings 38 forming walls 39 which act as stays to resist the lateral, bursting pressure in the interior of the section.

As already indicated, each of the side sections 28 and 29 are identical with the intermediate section above described, so far as the upper portions thereof are concerned. The latter differ only in respect of the dependent portions 55 which enclose one side of the combustion space.

The side sections 28 and 29 communicate with each other and with the front section 22 and the back section 25 at the upper ends thereof by means of nipples 42, preferably disposed above the water line of the boiler, and at the lower ends thereof by nipples 41. Similarly, the intermediate sections 30 and 31 communicate with each other and with the sections 22 and 25 at the upper ends thereof by nipples 42, also preferably disposed above the water line, and at the lower ends by nipples 43.

When the boiler is built, the front and back sections 22 and 25 are mounted in the usual manner and the side and intermediate sections 28, 29, and 30, 31, respectively, are disposed in groups of pairs in end to end relation, successive groups across the boiler being arranged with the fins 36 of each group contacting with the adjacent surfaces 45 of the adjoining group of sections. This disposition spaces the intermediate sections from each other and from the left group of side sections, as viewed in Fig. 2, to form a plurality of gas passages 46. The right group of side sections, as viewed in said figure, are 15 reversed in position relative to the left group and are disposed with the fins 36 touching each other to form a gas passage 47 of slightly greater width than the passage 46. In order to assist in deflecting the hot gases while 20 passing between the sections, the intermediate sections 30 and 31 have formed on the surfaces 45 thereof a pair of spaced, parallel ribs 44 extending across the length of the sections and disposed so that one rib is located slightly above each one of the fins 35 25 on the side or intermediate section immediately adjacent. As a result of the foregoing construction, the gas passages 46 and 47 are provided with a plurality of baffles which 30 act to control the movement of the hot gases as more fully described hereinafter.

In addition to the arrangement heretofore described, the rear side and intermediate sections 29 and 31 are provided with channels 35 48 across the chambers 34 thereof, which when the sections are assembled in the boiler form passages for delivering the flue gases to a smoke box 49 and thence to a stack 50. Steam generated by the boiler may be removed through a pipe 51 and the return line 40 is represented by the pipe 52. A shield 53 covers the sections of the boiler and over it may be laid the usual heat insulating covering.

45 The operation of my improved boiler will now be described.

Assuming a water level in the boiler as indicated by the numeral 54 and an appropriate fuel bed supported on the grates 21, 50 the combustible gases rising from said bed will pass upwardly through the passages 46 and 47 between the respective sections until they strike the fins 36 when they will be deflected through the passages 37 at the end thereof and caused to make a traverse across the length of each section between the fins 36 and the undersides of the chambers 34 of each section. In this connection, it will be understood that the sides of the chambers 34 55 in each group of sections are placed in contiguous relation with the sides of the sections of the adjoining groups, thus denying the passage of gas upwardly therebetween and confining its movement as before stated.

60 65 This general movement of the gas is identi-

cal between each pair of section groups and the gas is ultimately directed through the several channels 48 to the smoke box 49.

During the passage between the sections, it is evident that the flow direction of the gas 70 will be subjected to frequent deflections by the fins 35 and 36 and the ribs 44, creating substantially a wave motion of the gas. In relation to this movement, the various heating surfaces of the sections are disposed so 75 as to be substantially normal to the flow of the gas at any indicated point, thus insuring the most effective break up of the gas and the abstraction therefrom of the utmost heat value. Moreover, the frequent change in direction of the gas promotes a thorough mixture of the combustible gases with the entering air and thereby securing a complete burning thereof.

Owing to the difference in thickness of the 80 columns 32 and the portions of the sections enclosed thereby, the absorption of heat by the water in the depressed portions will be more rapid than that by the water in the columns, resulting generally in a circulation of water in each section which is 85 down through the columns 32 and up through the depressed portion, the steam being liberated at the surface 54 in the chambers 34. The rate of heat absorption is further enhanced by the fact that the total heating surface of each section is larger than that indicated by the overall dimensions thereof. Despite this favorable condition for efficient 90 heat transfer, there is no possibility of the water being driven from the sections under forced firing, by reason of the relatively large capacity of the back water legs 25 which serve substantially as water tenders for the side and intermediate sections and the provision for free and rapid circulation between 95 said legs and sections. In view of the rapid steaming capacity of the unit, the chambers 34 are made sufficiently large to promote a satisfactory disengagement of the steam from the water at the surface of the latter, thus obviating any danger of foaming.

As before stated, the character of the movement of the gases between the sections not only secures the complete combustion thereof, 100 but the length of the fire travel also insures that sufficient time is allowed to obtain the maximum heat value of the gases without affecting the maintenance of a proper draft through the boiler.

From a manufacturing and operating standpoint, my improved boiler is characterized by certain important advantages. The similarity between the sections simplifies the pattern necessities and the casting thereof, 105 while the sections may be easily assembled as hereinbefore described at low cost. In addition, the boiler is readily accessible for cleaning and repairs.

While I have shown one set of elements and 110

combinations thereof for effectuating my improved boiler, it will be understood that the same are intended for purpose of illustration only and in nowise to restrict the device to the 5 exact forms and structures shown, for many changes may be made therein without departing from the spirit of my invention.

I claim.

1. A boiler having side and intermediate, 10 water-containing sections, each section comprising upright end, upright intermediate, and transverse ducts, all of said ducts being in communication, said side sections having depending water legs communicating with 15 the ducts of the corresponding sections, front and rear water legs communicating with all of said sections, the intermediate sections being disposed above the source of heat and said side, front and rear water legs defining 20 the walls of a fire box.

2. A boiler having a series of water containing sections arranged side by side, each section comprising upright end and upright intermediate ducts, and transverse ducts 25 placing the upright and intermediate ducts in communication, some of the upright ducts being of uniform cross-sectional area throughout and the remaining upright ducts of progressively increasing cross-sectional 30 area, and a water reservoir communicating with said sections only at the upper and lower ends thereof.

3. A boiler having a series of water containing sections arranged side by side, each 35 section comprising upright end and upright intermediate ducts, and transverse ducts placing the end and intermediate ducts in communication, some of the upright ducts being of uniform cross-sectional area throughout 40 and the remaining upright ducts of progressively increasing cross-sectional area, and front and rear water legs constituting a water tender and in communication with said sections only at the lower and upper ends 45 thereof.

4. A boiler having a series of water containing sections of relatively small volume and large surface area of which each comprises upright end ducts of uniform cross-sectional 50 area throughout, upright intermediate ducts of progressively increasing cross-sectional area and transverse ducts placing the end and intermediate ducts in communication, and a water leg in communication with each section only at the upper and lower ends 55 thereof, the water legs being of relatively large volume as compared with said sections and being in communication with each other.

60 5. A boiler having a series of water containing sections enlarged at their upper ends to form steam chambers, the remaining portions of said sections being of relatively small volume and large surface area and comprising end ducts of uniform cross-sectional area 65

throughout, intermediate ducts of progressively increasing cross-sectional area and transverse ducts placing the end and intermediate ducts in communication, the end and intermediate ducts communicating with said steam chambers, and water legs of relatively large volume as compared with said sections and in communication with the latter only at the lower ends and at the steam chambers, said water legs being in communication with each other. 70

6. A boiler having a series of water containing sections arranged side by side, each section comprising upright end and upright intermediate ducts, and transverse ducts 75 placing the end and intermediate ducts in communication, the end ducts and transverse ducts being of uniform cross-sectional area throughout and the intermediate ducts of progressively increasing cross-sectional area, 80 each of said sections being enlarged at its upper end to provide a steam chamber with which said upright ducts are in communication, and water legs in communication with the sections only at the lower ends thereof 85 and at the steam chambers, said water legs being in communication with each other only at their upper and lower ends. 90

7. A boiler having a series of water containing sections arranged side by side, each section comprising upright end and upright intermediate ducts, and transverse ducts placing the end and intermediate ducts in communication, the end ducts being of uniform cross-sectional area throughout and the intermediate ducts of progressively increasing cross-sectional area, 100 said sections being formed at their upper ends with steam chambers with which said upright ducts communicate, and water legs in communication 105 with said sections only at the lower ends thereof and at the steam chambers, said water legs being in communication with each other at their upper and lower ends. 110

In testimony whereof, I affix my signature. 110
JOHN B. BERNHARD.
